(74) *Attorney, Agent, or Firm* — Barley Snyder

(57) **CLAIM**

The ornamental geodesic display connector design, as shown and described.

DESCRIPTION

FIG. 1 is a top, front, left side perspective view of a geodesic display connector, showing the new design;

FIG. 2 is a front elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a rear elevation view thereof;

FIG. 8 is a bottom, front, left side perspective view thereof;

FIG. 9 is a top, front, left side perspective view of a second embodiment of a geodesic display connector, showing the new design;

FIG. 10 is a front elevation view of the geodesic display connector in FIG. 9;

FIG. 11 is a left side elevation view of the geodesic display connector in FIG. 9;

FIG. 12 is a right side elevation view of the geodesic display connector in FIG. 9;

FIG. 13 is a top plan view of the geodesic display connector in FIG. 9;

FIG. 14 is a bottom plan view of the geodesic display connector in FIG. 9;

FIG. 15 is a rear elevation view of the geodesic display connector in FIG. 9; and,

FIG. 16 is a bottom, front, left side perspective view of the geodesic display connector in FIG. 9.

The broken lines shown in the drawings are included for the purpose of illustrating environmental structure and form no part of the claimed design.

1 Claim, 8 Drawing Sheets
